W. M. SIMON

FOLDING BED

Filed Feb. 1, 1926

UNITED STATES PATENT OFFICE.

WILLIAM M. SIMON, OF CHICAGO, ILLINOIS, ASSIGNOR TO QUALITY METAL BED CO., OF CHICAGO, ILLINOIS, A CORPORATION OF ILLINOIS.

FOLDING BED.

Application filed February 1, 1926. Serial No. 85,304.

My invention relates to improvements in folding beds, and it consists in the combinations, constructions, and arrangements herein described and claimed.

5 An object of my invention is to provide an improvement over that form of the device shown in my co-pending application on folding bed, Serial No. 78,995, filed January 2, 1926. The improvement consists in a dashpot for controlling the swinging of the bed frame into closed position, this dashpot cooperating with spring means for swinging the bed frame into folded position.

15 A further object of my invention is to provide a device of the type described which is extremely simple in construction, and which prevents the vibration of the bed frame after it has been swung into closed position.

20 Other objects and advantages will appear in the following specification, and the novel features of the invention will be particularly pointed out in the appended claim.

25 My invention is illustrated in the accompanying drawings, forming part of this application, in which

Figure 1 is a longitudinal section through the device, and

30 Figure 2 shows the device operatively applied to my improved folding bed.

35 In carrying out my invention, I make use of the bed construction illustrated and described in my co-pending application. To the spring frame 1 of the bed, I secure a piston A, and to the frame 2 of the bed, I 40 secure a cylinder B. The piston A and the cylinder B form the dashpot. It is obvious that the dashpot may be applied to folding beds other than that disclosed in Figure 2 without departing from the spirit and scope of my invention. The purpose of the dashpot is to control the movement of the spring frame 1 just prior to the stopping of the spring frame in closed position.

45 The special construction of the dashpot is shown in Figure 1, and it will be noted from this figure that the dashpot comprises a cylinder 3 having an outwardly flared open end 4, this flared portion being provided for guiding a piston 5 into the cylinder. The cylinder 3 has an air escape opening 6 therein, this opening being small enough to cause the piston to travel slowly toward the closed end 7 of the cylinder.

50 The piston A and the cylinder B are

mounted on the bed in a novel manner to 55 permit the parts to swing with respect to their supporting members as the piston enters the cylinder. I will first describe the means for mounting the cylinder on the bed. This means comprises a strap 8 which is secured to the frame 2 by means of rivets 9 or the like. Midway between the sides of the frame 2 I secure a cylinder-supporting member 10 by means of bolts 11. The member 10 is pivotally connected at 12, see Figure 2, to a cylinder-carrying yoke 13.

It will be noted from Figure 1 that the yoke 13 is provided with a cam edge 14 against which spring-pressed plungers 15 70 yieldingly contact. The plungers 15 are carried by the member 10, and two or more of these plungers may be provided if desired. In Figure 1, I show the cylinder 3 in the position it will assume when the piston 5 is received in the cylinder, while in Figure 2, I 75 show the relative positions of the piston and the cylinder when the spring frame 1 is in open position.

The purpose of the spring-pressed plungers 15 is to hold the cylinder 3 in the position into which it is swung, i. e., in the position shown in Figure 1, or the position shown in Figure 2. The edge 14 is cammed slightly to permit the plungers 15 to exert a force substantially at right angles to the surface 14, regardless of the position the surface 14 assumes with respect to the plungers.

80 The special piston construction is shown in Figures 1 and 2, and it will be noted from Figure 2 that the piston rod 16 is pivotally secured at 17 to a bracket 18, the bracket in turn being secured to the spring frame 1 by means of a cap screw 19. The bracket has a recess 20 therein in which the piston rod 16 85 swings.

85 A leaf spring 21 of the shape shown in Figure 1 is disposed between the spring frame 1 and the bracket 18, and has its free end bearing against a finger 22, this finger being rigidly secured to the piston rod 16. 90 When the piston 5 is free of the cylinder 3, the spring 21 swings the piston rod and causes the rod to abut the inner edge of the recess 20. This position aligns the piston 5 with the flared opening 4 as the piston enters the cylinder, thus providing a device which 95 will operate very efficiently. After the piston 5 has once entered the flared portion 4, 100

further movement of the piston into the cylinder will cause the piston rod 16 to swing about the pivot 17 into the position shown in Figure 1, and will also cause the cylinder 3 to swing from the position shown in Figure 2 into a substantially horizontal position.

From the foregoing description of the various parts of the device, the operation thereof may be readily understood. As heretofore stated, the device may be applied to folding beds other than the type shown in the drawing. The operator in closing the bed, lifts the foot portion 23 of the bed, thus causing the spring frame 1 to pivot about the rod 24. Springs 25 aid the operator in lifting the spring frame into closed position.

It will be noted that as the spring frame 1 nears the end of its swing into vertical position, the momentum of the spring frame, together with the fact that as the spring frame nears vertical position, the springs 25 will have less weight to lift, will cause the springs 25 to move the spring frame 1 more quickly. If this quickened movement were permitted at the end of the swinging of the spring frame into closed position, the abrupt stopping of the spring frame when in closed position would cause the frame to vibrate. The

function of the dashpot is to overcome this tendency of the spring frame to vibrate.

The piston 5 is designed to enter the cylinder 3 at the point where the spring frame 1 nears the end of its movement. The slow exhaust of air through the opening 6 causes the piston 5 to create a force which opposes the force of the springs 25. The springs 25 are strong enough to cause the piston 5 to move into the position shown in Figure 1, but as soon as the piston reaches this position, the force exerted by the spring 25 has been expended and the frame will remain in closed position without vibrating for a short length of time as is the case where the dashpot is not provided.

I claim:

The combination with a folding bed, of a cylinder pivotally carried by said bed and having a flared open end, a piston carried by the swingable frame of said bed and being pivotally connected thereto, spring means for yieldingly holding said piston in a position to permit the piston to readily enter the cylinder, and spring means for yieldingly holding the cylinder in the various positions into which it is swung.

WILLIAM M. SIMON.
